UNITED STATES PATENT OFFICE.

GEORGE H. QUENNARD, OF ALLENDALE, NEW JERSEY.

DESIGN FOR AN INTERLOCKING TILE.

40,358.

Specification for Design.

Patented Nov. 16, 1909.

Application filed August 20, 1909. Serial No. 513,898. Term of patent 14 years.

To all whom it may concern:

Be it known that I, GEORGE H. QUENNARD, a citizen of the United States, and a resident of Allendale, in the county of Bergen and State of New Jersey, have invented a certain new, original, and ornamental Design for Interlocking Tiles, of which the following is a specification.

The accompanying drawing shows a plan

view of an interlocking tile made in accordance with my improved design.

What I claim is:—

The ornamental design for an interlocking tile, as shown.

GEORGE H. QUENNARD.
